UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FILLING-REPLENISHING LOOM.

Application filed February 13, 1922. Serial No. 536,110.

To all whom it may concern:

Be it known that I, ISAAC SNOW, a citizen of the United States, residing at Lawrence, in the county of Essex and State of Massachusetts, have invented an Improvement in Filling-Replenishing Looms, of which the following description, in connection with the accompanying drawings, is a specification, like characters on the drawings representing like parts.

This invention relates to filling replenishing looms wherein a new supply of filling is furnished the loom prior to the complete exhaustion of the old filling.

Looms of this general character are usually provided with stopping mechanism for bringing the loom to rest on the occurrence of some fault, as for instance the breakage of a warp or filling thread. In such cases it is customary for the loom attendant to move the shuttle home in the shuttle box by hand, so that on the following pick the picking mechanism may serve to perform its picking function and throw the shuttle into the other box. When the loom is again started by power as by movement of the stopping mechanism into loom running position, the shuttle may still contain a working supply of filling, and under such conditions it is desirable that the filling replenishing mechanism may not operate to replenish the filling when the loom is started.

An important feature of the present invention consists in means for preventing the replenishment of filling through the feeler and controlling means until after the loom has been restored to full running condition. In carrying this feature of the invention into effect means is provided to be positioned or actuated by movement of the shipper into stopping position so constructed and arranged that the controlling mechanism for controlling replenishment of filling will be rendered ineffective for this purpose until after the shipper has been moved to loom running position.

In the present instance of the invention the feeler is mounted for movement by the filling towards the front of the loom and also in a direction longitudinally of the shuttle box on a detecting beat before the shuttle comes to rest in the shuttle box. The construction is such that the feeler acts

through the controlling mechanism to prevent replenishment of filling when the feeler is given its movement longitudinally of the shuttle box on a detecting beat, and to initiate replenishment of filling when, upon substantial exhaustion of the filling in the shuttle, the feeler fails to be moved longitudinally of the shuttle box.

The novel features of the present invention and the new combination of parts will best be made clear from the following description and accompanying drawings of one form or embodiment thereof.

In the drawings:

Fig. 1 is a perspective view of the detecting side of the loom showing the feeler and associated parts.

Fig. 2 is a plan view showing the position assumed by the parts on a detecting beat as the shuttle moves longitudinally in the shuttle box.

Fig. 3 shows the relative position of parts when, on a detecting beat, the feeler fails to be moved longitudinally in the shuttle box owing to the substantial exhaustion of filling; and

Fig. 4 is a plan view showing the feeler held or locked in its non-replenishing position by means actuated by the stopping mechanism as the latter is moved into stopping position.

The loom frame 1 has at each side thereof a bracket 2 provided with bearings 3, one only of which is shown, for the usual transverse or rock shaft 4. Extending upwardly from the shaft 4 is the arm 5 to which is connected at 6 the arm 7, the rear end portion of which is adapted to be engaged by an actuator 8. The actuator 8 may appropriately be formed as part of or connected to the weft hammer or cam follower, and the construction is such that normally the actuator 8 would strike and move the arm 7 to cause replenishment of filling unless, on a detecting beat, the arm 7 is moved into inoperative relation with the actuator by the filling replenishing controlling means.

Pivots mounted on the loom frame is a controller for controlling the position of the arm 7, and such controller is in turn governed by the feeler. In the present instance of the invention the controller consists of an arm 9 pivotally supported on an axis 10 for rocking movement thereon, and

such controller 9 is under the impulse of a spring 11 normally tending to turn the controller contra-clockwise so that the end portion 12 of the controller, under the actuation of the spring 11 will normally hold the arm 7 in position to be engaged by the actuator 8.

The other end of the controller 9 is provided with a notched portion 13 having a cam surface 14.

Mounted upon the loom frame is the feeler which has capacity for movement towards and from the front of the loom and also in a direction transversely of the loom or longitudinally of the shuttle box.

In the present instance the feeler 15 is carried by a feeler stand 16 mounted adjustably on the loom frame by a bolt 17 passing through a slot 18 on the extended arm 19.

20 The front end portion of the feeler passes through a rocking bearing 20 which is supported at its top and bottom portions for rocking movement by the bridge pieces 21, the construction being such that while the 25 rocking bearing 20 may rock about its pivotal support 22, the feeler 15 may move in the slotted portion of the rocking bearing towards and from the front of the loom.

20 The feeler stand 16 has a rear bearing portion 23 provided with an elongated slot 24 through which the feeler extends, and a spring normally holds the feeler in its rearward feeling position. In the present instance this spring is shown at 25 one end of which is connected adjustably to an arm 26 by means of the openings 27 and the other end of the spring 25 is similarly connected to the feeler as at 28, the construction being such that the spring 25 normally acts to hold 35 the feeler in its rearward feeling position and against one end of the elongated bearing slot 24, but with permissive movement of the feeler towards and from the front of the loom and in a direction longitudinally of the 40 shuttle box.

30 The lay 29 is of usual construction and the front wall of the shuttle box has an opening 30 through which the feeler projects to feel for the filling in the shuttle on a detecting beat. The shuttle 31 is likewise provided with an opening 32 in its side wall through which the feeler may enter to feel for the filling 33 on the filling carrier bobbin 34 mounted in the shuttle, the construction being such that on a detecting beat the toothed end 35 of the feeler will enter the shuttle before the shuttle comes to rest in the shuttle box, and if a working supply of filling is present in the shuttle, the feeler 15 will be 55 moved with the shuttle as it goes fully home into the shuttle box. Under the conditions stated the feeler 15 will ride along the cam portion 14 of the controller 9 and turn the controller clockwise on a detecting beat to thereby place the end of the arm 7 in an in-

operative position with relation to the actuator 8.

Should the filling be substantially exhausted on a detecting beat, however, as indicated in Fig. 3, the feeler 15 will fail to be moved longitudinally in the shuttle box by the shuttle as it goes fully home in the box and thereby the feeler will fail to turn the controller so that the end of the arm 7 will be engaged by the actuator 8, and through the usual train of mechanism will effect replenishment of filling when the shuttle reaches the replenishing side of the loom.

In looms of this general type stopping mechanism is provided for stopping the loom when some fault occurs, as for instance the breakage of a warp thread, or of the filling thread, or of the harness mechanism. Such stopping mechanism is of usual construction and is controlled by a train of mechanism including a shipper. Since the particular construction of the stopping mechanism forms no essential part of the present invention, such mechanism is herein typified by the shipper 36 which, when the loom is running, is held in the notch 37 formed in the shipper stand 38. When a fault occurs such as the breaking of a warp thread, or a weft thread, or of the harness connections, the shipper is thrown from its holding notch as usual in this class of looms and under the actuation of the usual shipper spring the shipper moves in the shipper slot 39 to the outer end portion thereof. Advantage is taken of this movement of the shipper to render the filling replenishing controller means ineffectual, and in the present instance the shipper stand has pivotally mounted thereon at 40 a bell crank lever, one end 41 of which is in the path of the shipper as it moves towards the outer end of the shipper notch, and the other end 42 of which carries a pin or roller 43 which, as the bell crank-lever is turned by engagement of the shipper with the end 41 of the bell crank, 100 renders the controlling mechanism ineffectual to replenish the filling.

In the present instance the bell crank lever has connected thereto a spring 44 which normally holds the bell crank in the position indicated by Figs. 1 and 2, with the end 41 of the bell crank crossing or partly crossing the shipper notch 39. As shown in the present instance the roller 43 on the bell crank engages the side of the feeler 15 when the bell crank is turned by the shipper, and the feeler 15 is thereby moved into its inclined position to render ineffectual the filling replenishing mechanism.

When a fault occurs in the operation of the loom, as for instance breakage or undue slackness of a warp thread, or from some other cause, and the shipper is disengaged from its holding notch as usual, it will engage the arm 41 of the bell crank as it moves 125

to the outer end of the shipper notch, turn the bell crank upon its pivot and move the feeler into its inclined or non-filling replenishing position.

- 5 The loom attendant may now correct the fault which caused loom stoppage and may by hand move the shuttle fully home in its shuttle box. He will then move the shipper to loom running position as indicated in
 10 Fig. 1, so that on the first detecting beat following restoration of the shipper to loom running position, the feeler will be engaged by the filling in the shuttle and be moved frontwardly thereby, and since the
 15 feeler is in its inclined or non-replenishing position filling replenishment will not be effected.

- In order to restore the bell crank to its normal position as indicated in Figs. 1 and
 20 2 when the loom is started as above indicated, the feeler is provided with a member or projection 45 against which the roller 43 of the bell crank bears, the construction being such that as the feeler moves frontwardly
 25 on the first detecting beat after restoring the shipper to loom running position, the member or pin 45 on the feeler will turn the bell crank or start it to turn and restore it to its normal position to thereby free the feeler
 30 and the controlling mechanism for effecting replenishment of filling when, on a detecting beat, filling is substantially exhausted in the shuttle.

- It may not always be necessary to provide the member or pin 45 on the feeler to restore the bell crank to its initial position but such construction is desirable as a trip for the bell crank to restore it to normal position only upon the detecting beat following movement of the shipper to loom running position.

- The construction shown and described constitutes a good practical form of the present invention, but the details may be varied within wide limits without departing from the true scope of the present invention as defined by the claims.

Claims—

1. In a loom provided with filling replenishing mechanism, controlling means for the replenishing mechanism including a feeler that enters the shuttle on a detecting beat and feels for the filling and upon substantial exhaustion thereof causes the controlling means to effect replenishment of filling, loom stopping mechanism for stopping the loom, and means rendered effective by movement of the stopping mechanism to stopping position to prevent replenishment of filling on the first beat-up following movement of the stopping mechanism to running position.

2. In a loom provided with filling replenishing mechanism, controlling means for the replenishing mechanism including a

feeler that enters the shuttle on a detecting beat and feels for the filling and upon substantial exhaustion thereof causes the controlling means to effect replenishment of filling, loom stopping mechanism for stopping the loom, and means positioned by movement of the stopping mechanism to stopping position for locking the controlling means from operating until after the first beat up following movement of the stopping mechanism to running position.

3. In a loom provided with filling replenishing mechanism, controlling means for the replenishing mechanism including a feeler that enters the shuttle on a detecting beat and feels for the filling and upon substantial exhaustion thereof causes the controlling means to effect replenishment of filling, loom stopping mechanism for stopping the loom, means positioned through movement of the stopping mechanism to stopping position for locking the controlling means from operating to call a change, and a trip operated on the beat-up movement of the lay after the stopping mechanism has been moved to running position for freeing the controlling means.

4. In a loom provided with automatic filling replenishing mechanism, controlling means therefor, including a controller moved into inoperative position by filling induced movement of the feeler, a feeler intermittently moved by the filling in the shuttle until said filling is substantially exhausted, loom stopping mechanism, and means operated by or through movement of the stopping mechanism to stopping position to temporarily render the said controlling means ineffectual to cause replenishment of filling until the first detecting beat following movement of the stopping mechanism to running position.

5. In a loom provided with automatic filling replenishing mechanism, controlling means therefor including a feeler which is intermittently moved by the filling in the shuttle, loom stopping mechanism for stopping the operation of the loom, and means operated by or through movement of the stopping mechanism to stopping position for rendering the said controlling means ineffectual to cause replenishment of the filling until after the feeler has been moved frontwardly following movement of the stopping mechanism to running position.

6. In a loom provided with filling replenishing mechanism, controlling means for controlling the operation of said mechanism including a feeler which feels for the filling in the shuttle on a detecting beat, stopping mechanism for stopping the loom, and a lock rendered effective by movement of the stopping mechanism to stopping position to hold the feeler from calling a change until the feeler has been moved frontwardly subse-

quent to movement of the stopping mechanism to loom running position.

7. In a loom provided with filling replenishing mechanism, controlling means for controlling the operation of said mechanism including a feeler which feels for the filling in the shuttle on a detecting beat, stopping mechanism for stopping the loom, a lock rendered effective by movement of the stopping mechanism to stopping position to hold the feeler from calling a change until after the stopping mechanism has been moved to loom running position, and means actuated by frontward movement of the lay for tripping the lock when the stopping mechanism has been moved to loom running position:

8. In a filling replenishing loom, the combination of a feeler mounted for movement towards and from the front of the loom and also for movement longitudinally of the shuttle, controlling mechanism for causing the replenishment of filling when the feeler indicates substantial exhaustion of the filling on a detecting beat, stopping mechanism, means operated by movement of the stop-

ping mechanism to stopping position for holding the feeler from operating through the controlling mechanism to call a change of filling until after the stopping mechanism is returned to loom running position and a feeler operated trip for said means.

9. In a filling replenishing loom, the combination of a feeler mounted for movement towards and from the front of the loom and also for movement longitudinally of the shuttle, controlling mechanism for causing the replenishment of filling when the feeler indicates substantial exhaustion of the filling on a detecting beat, stopping mechanism, means operated by movement of the stopping mechanism to stopping position for holding the feeler from operating through the controlling mechanism to call a change of filling, and means for tripping the holding means when the loom is run on return of the stopping mechanism to running position.

In testimony whereof, I have signed my name to this specification.

ISAAC SNOW.
